ILLUMINATED ORNAMENT FOR SHOES

Joseph De Merolis and Alexander Di Lizio,
Philadelphia, Pa.

Application April 4, 1949, Serial No. 85,414

6 Claims. (Cl. 240—6.4)

1

Our invention relates to a new, useful and decorative illuminated ornament that can be attached to any article of wearing apparel, such as a shoe, collar, the top of a sports stocking, a coat lapel, hat, dress or other suitable item on which the device can be conveniently supported. Aside from the illuminating means, an essential feature of the invention comprises the ornamental element which may be in the form of a shoe bow or buckle, rosette, necktie, flower or various devices representative of items in the insect, animal and vegetable kingdoms.

An object of the invention is to provide a structure, that may be mounted wherever desired, including electric lamps, such as flash light bulbs, a battery, a switch, the necessary circuit conductors and an ornamental element all combined in a single unitary article.

Another object of this invention is to provide, in an article of the kind mentioned, a foundation consisting of a panel on which is fixedly mounted lamp sockets, a battery holder, a switch, suitable circuit conductors including said switch, battery holder and a terminal contact to be engaged by the center terminal of a dry cell battery, and an attaching clip to temporarily fasten the device to a supporting article of wearing apparel, said lamp sockets adapted to receive electric lamps or bulbs which detachably retain an ornamental item on the face of the foundation.

A further object of this invention is to form the battery holder and attaching clip from a single strip of electric conductive material to assist in maintaining a low cost of manufacture.

A still further object of the present invention is to provide a detachable ornamental element so fashioned that it may be readily and quickly removed from or assembled upon the foundation. This permits easy substitution of a new ornamental element for an old or damaged one, or the replacement of one type for another, either of different color, configuration or both.

With the above and other objects in view this invention consists of the details of construction and combination of elements hereinafter set forth and then designated by the claims.

In order that those skilled in the art to which this invention appertains may understand how to make and use the same we will describe its construction in detail, referring by numerals to the accompanying drawing forming a part hereof, in which:

Fig. 1 is a perspective view of a shoe with the illuminated ornament attached to one part thereof, thereby illustrating one instance where the device may be employed.

2

Fig. 2 is an enlarged fragmentary side of the shoe and a portion broken away to show the manner of mounting the illuminated ornament thereon and illustrating one method of intermittently lighting the lamps through the movements of a person's foot, the instep of which is shown in dotted lines.

Fig. 3 is an obverse face view of the foundation without the ornamental element and lamps.

10 Fig. 4 is a reverse face view thereof with the battery in place.

Fig. 5 is a section on the staggered line 5—5 of Fig. 4, the thickness of the panel being exaggerated.

15 Fig. 6 is a section on the line 6—6 of Fig. 4.

Fig. 7 is a front view of an ornamental element for detachable connection to the foundation, said ornamental element being shown as a bow only for illustrative purposes.

20 In carrying out our invention as herein embodied 10 represents the foundation structure including a panel 11 of stiff insulating material, such as "Bakelite," cardboard or even heavy paper. The panel is of any appropriate or desirable outline or configuration and suitable size depending to some extent upon the size of the support and surrounding features with which the device is to be used.

The panel 11 has two holes 12 and 13 therethrough and where said panel is oblong these holes are located near the ends and adjacent the lower edge. In the holes 12 and 13 are fixedly mounted the lamp sockets 14 and 15, respectively, with the open ends accessible from the front of the foundation or the panel, in particular. The center terminals of said lamp sockets 14, 15 are connected by a common conductor 16, such as an insulated wire, with a terminal contact 17, preferably having some inherent resiliency, secured to and projecting from the reverse face of the panel by a suitable fastening device, such as a screw 18 and nut 19.

30 A strip of electric conductive material has one, the upper, end bent upon itself in loop configuration to form a battery holder 20 with said upper end imposed on the body of the strip, Figs. 5 and 6, and then said strip is projected downwardly a suitable distance and the other or lower end bent outwardly and back upon itself to form a spring 40 attaching clamp or clip 21 of hook formation whereby the device may be detachably mounted on the edge of the vamp of a shoe 22, for example, in a buttonhole, over the edge of a coat lapel, collar, top of a stocking or other article of wearing apparel. This combined battery holder loop 50 and attaching clamp structure is secured to the

45

55

A strip of electric conductive material has one, the upper, end bent upon itself in loop configuration to form a battery holder 20 with said upper end imposed on the body of the strip, Figs. 5 and 6, and then said strip is projected downwardly a suitable distance and the other or lower end bent outwardly and back upon itself to form a spring 40 attaching clamp or clip 21 of hook formation whereby the device may be detachably mounted on the edge of the vamp of a shoe 22, for example, in a buttonhole, over the edge of a coat lapel, collar, top of a stocking or other article of wearing apparel. This combined battery holder loop and attaching clamp structure is secured to the

reverse face of the panel 11 by a single fastening means 23, such as a screw and nut, projected through the two thicknesses of the strip where the upper end of the strip, from which the battery holder and attaching clamp are formed, overlap.

A switch member 24 includes a resilient and bendable switch 25 having oppositely projecting side arms 26 and 27 that bridge or straddle the battery holder and attaching clamp structure, Figs. 5 and 6, so that no part of said switch can touch said holder and clamp structure which might cause a short circuit. The arms 26, 27 have fingers 28, 29, respectively, bent therefrom so that the switch member, as a whole, can be fastened to the reverse face of the panel by fastening devices 30, such as screws and nuts. The fastening devices 30 are projected through fingers 28, 29, the panel and through connector clips 31 and 32 preferably located on the obverse face of the panel. These connector clips are of electric conductive material and are secured to the other circuit sides of the sockets 14 and 15, respectively, as by being soldered to the exterior side surfaces of said sockets.

A battery or dry cell 33 snugly fits in the loop shaped battery holder 20 and the latter makes electrical contact with one pole of said battery, as through the side walls thereof while the other pole or center end terminal engages the terminal contact or post 17. As a small flashlight battery is generally employed in this device and since such a battery is usually enclosed in an insulating jacket the latter is removed before the battery is mounted in the holder 20.

As the switch 25 is flexible and bendable there might be times when said switch would contact the spring attaching clamp 21. This would cause a short circuit and to prevent such a possibility these parts are insulated from one another. This may be accomplished by adding a coating of insulating material to the adjacent face of either the switch or attaching clamp and for purposes of illustration such insulating material is shown at 34 applied to the attaching clamp 21 or that portion thereof facing the switch.

The ornamental element 35 is shown herein as a bow, merely for purposes of illustration since such ornamental element may be of any desirable configuration, such as an imitation flower, reproductions of animals, insects or other natural objects, comic figures and the like.

Said ornamental element has two holes 36 spaced equal to the spacing of the clamp sockets 14 and 15 whereby said ornamental element may be spaced over the forward open ends of the sockets and against the panel and held in place by the lamps or electric light bulbs 37 screwed into said sockets and engaging the front face of the ornamental element. Additional ornamentation may be provided, if desired, by the application of rings 38 surrounding the necks of the lamps.

It is obvious that the device can be employed in various capacities, for example, as a necktie, an ornament for coats or dresses or a decorative article on a shoe, as shown. When used on a shoe the movable switch 25 may be located in proximity to the instep, represented by dotted lines 39 in Fig. 2, of the wearer of the shoe 22. Then during the process of taking a step the foot will bend and the instep will force the switch into contact with the battery holder 20 to complete a circuit through the battery, the terminal contact 17, conductor 16 to one side of the sockets 14 and 15, thence from the other side of said

sockets and through connector clips 31 and 32, fastening devices 30, fingers 28 and 29, and arms 26 and 27 back to the switch 25. As the wearer's foot is straightened, the switch will retract to open the circuit. Thus as the wearer walks the lights will flash intermittently and produce a pleasing effect. In other instances the switch can be actuated manually and when it is desired that the lamps burn continuously said switch can be bent to be constantly in contact with the battery holder. By sliding the battery backward within its holder away from the contact post 17 the circuit will be opened and the light cannot be accidentally lit when the device is packed for storage or shipment.

As the ornamental element is detachable it can be removed and replaced by another. For instance, if the device is to be transferred from a shoe of one color to a shoe of another color, the ornamental element of one color can be removed from the foundation and replaced by another of the proper or desired different color.

Of course we do not wish to be limited to the exact details of construction herein shown and described as these may be varied within the scope of the appended claims without departing from the spirit of our invention.

Having described our invention what we claim as new and useful is:

1. An illuminated ornament for removable mounting on an article of wearing apparel consisting of a panel, a dry cell holder of electric conductive material mounted on the back of said panel, a contact post on the back of the panel to be engaged by a terminal of a dry cell assembled in the holder, electric lamp sockets mounted on the panel with their open end at the front of said panel and adapted to receive lamps, a resilient and bendable switch mounted on the panel with a portion of said switch located for cooperation with the dry cell holder, an electric circuit including the holder, the lamp sockets, the dry cell and lamps when assembled in the holder and sockets, respectively, and said switch, and means to removably attach the panel to a suitable support.

2. An illuminated ornament comprising, in combination, a panel of insulating material, a unitary dry cell holder and resilient attaching clamp produced from a single strip of electric conductive material having one end bent into loop formation and the opposite end fashioned into hook-like shape to be placed over the edge of a support, means to fasten said holder and clamp structure to the reverse face of the panel, a dry cell removably and slidably mounted in the holder and in electrical contact with said holder, a resilient contact post mounted on the reverse face of the panel in line with the axial center of the holder and to be engaged by the end terminal of the dry cell, electric lamp sockets mounted in holes in the panel with the open ends of said sockets on the obverse side of the panel, lamps removably mounted in said sockets, one pole of each of said sockets being electrically connected with each other and the contact post, a resilient and bendable switch member having a portion in alignment with a side of the holder with which it is to contact to close a circuit through the lamps, all other parts being out of contact with holder and clamp structure and insulated therefrom by the panel, means to connect the other pole of each socket with the switch, and an ornamental element imposed

on the obverse face of the panel and detachably held in place by the lamps.

3. The illuminated ornament structure according to claim 2 wherein the means to connect the other pole of each socket with the switch consists of connector clips of electric conductive material secured to said sockets and positioned on the obverse face of the panel, and fastening devices projected through said connector clips, the panel and portions of the switch.

4. The illuminated ornament structure according to claim 2 wherein the switch member includes a pair of oppositely projecting arms to bridge over the holder and clamp structure, and fingers projecting from the arms and engaging the reverse face of the panel.

5. The illuminated ornament structure according to claim 2 wherein the ornamental element consists of a decorative article having holes therethrough spaced according to the spacing of the lamp sockets.

6. An illuminated ornament to be worn on a shoe and consisting of a panel, an attaching clip secured to the reverse face of the panel to assume a position between the shoe vamp and wearer's foot when the panel is imposed on the exterior of the shoe vamp, an ornamental article on the obverse face of said panel, a dry cell battery holder of electric conductivity on the reverse side of said panel, a dry cell battery in said

15

30

holder, a switch member on the reverse face of said panel to be engaged by the instep of the person wearing the shoe with the ornament thereon each time a step is taken, a contact post 5 on the panel for engagement by one terminal of the battery in the holder, and a lamp projecting through the ornamental article and panel and in circuit with the battery, contact post, battery holder and switch member whereby said lamp 10 will be lit at each step taken by the wearer of the shoe.
